CLAIM

We claim the ornamental design for an outer appliance panel, as shown and described.

DESCRIPTION

FIG. 1 is a first side perspective view of the outer appliance panel of the present invention;

FIG. 2 is a second side perspective view of the outer appliance panel of the present invention;

FIG. 3 is a third side perspective view of the outer appliance panel of the present invention;

FIG. 4 is a first side elevation view of the outer appliance panel of the present invention;

FIG. 5 is a second side elevation view of the outer appliance panel of the present invention;

FIG. 6 is a bottom plan view of the outer appliance panel of the present invention;

FIG. 7 is a top plan view of the outer appliance panel of the present invention;

FIG. 8 is a third side elevation view of the outer appliance panel of the present invention; and,

FIG. 9 is a fourth side elevation view of the outer appliance panel of the present invention.

The broken lines in the figures are for contextual purposes or show the environment and form no part of the claimed design.

1 Claim, 8 Drawing Sheets

Related U.S. Application Data
